UNITED STATES PATENT OFFICE.

FREDERICK AUGUSTUS WILSON, OF NEW YORK, N. Y.

VENTILATING-REGISTER.

1,070,312.

Specification of Letters Patent.

Patented Aug. 12, 1913.

Application filed November 9, 1911. Serial No. 659,294.

To all whom it may concern:

Be it known that I, FREDERICK AUGUSTUS WILSON, a citizen of the United States, and a resident of the city of New York, borough 5 of Brooklyn, in the county of Kings and State of New York, have invented a new and Improved Ventilating-Register, of which the following is a full, clear, and exact description.

10 Among the principal objects which the present invention has in view are: to provide a register of the character named with a plurality of louvers and means for adjusting and holding the said louvers in adjusted 15 position; to provide means for limiting the full opening of the said louvers; and to simplify and economize the construction.

One embodiment of the present invention is disclosed in the structure illustrated in the 20 accompanying drawings, forming a part of this specification, in which like characters of reference denote corresponding parts in all the views, and in which—

Figure 1 is a perspective view of a register 25 constructed and arranged in accordance with the present invention; Fig. 2 is a vertical cross section of a register constructed in accordance with the present invention, the section being taken on the line 2—2 in Fig. 3; Fig. 3 is a horizontal section taken on the 30 line 3—3 in Fig. 2, showing a fragment of the construction; and Fig. 4 is a vertical section taken on the line 4—4 in Fig. 3, showing a fragment of the construction.

35 As seen in the accompanying drawings, two doors or louvers 9, 9 are hingedly mounted at the back of a register box 10 and in superposed relation. The box 10 is structurally provided with an opening in 40 the back, which opening is closed by the said louvers when dropped to rest upon the box. By using a plurality of louvers the air admitted into or passed from the register box is more evenly equalized for distribution 45 over the area of the grill 11 which covers the face of the box.

The louvers are provided with hinges 12, 12, one of the said hinges being secured to the box structure and the other being mounted 50 upon a cross brace 13. Adjacent the said hinges each of the louvers is provided with a box-like extension 14. The side walls of the extensions 14 form bearings for the pivot pins 15, 15. The pivot pins 15 in this manner are set beyond or protruded from the back of the louvers 9. This arrangement of

the pins 15 in relation to the louvers 9 insures the full closure of the said louvers when the links 16 are drawn upon to close the said louvers. The links 16 are connected 60 by means of the screw 17 and the bolt 18 to the upper and lower end, respectively, of the slide bar 19. The slide bar 19 is mounted to slide on the vertical rib 20, and the screw 17 and bolt 18 are extended through the slots 65 21 provided in the said rib 20, as seen best in Figs. 1 and 4 of the drawings. It is to form a drag or brake on the bar 19 to hold the same in fixed position relative to the rib 20 that I have provided the washers 22, 22 70 to surround the bolt 18, one of said washers forming a bearing for the spiral spring 23 which is compressed or disposed under tension by the nut 24 threaded on the said bolt 18. By this construction, wherein the 75 spring 23 is employed, a yielding pressure is imposed on the washer 22 at the opposite side of the rib 20 to retard the action of the slide bar 19. While I here describe the construction and operation employing the 80 spring 23, it will be understood that any suitable resilient material, such as a small piece of rubber jack, may be employed.

To shift the slide bar 19 vertically, and to thereby open or close the louvers 9, I employ the toothed segment 25 which is fixedly mounted upon the shaft 26. The shaft 26 is extended to the outer side of the grill 11, and is there provided with a fixed crank arm 27. The crank arm 27 is provided with 90 any suitable engagement means, that shown in the drawings and preferred by me being the handle 28. The teeth 29 of the segment 25 are, as shown best in Fig. 4 of the drawings, purposely separated to accommodate 95 and cheapen the construction of the bar 19 wherein the holes 30 are provided as sockets for the reception of the teeth 29.

In the normal position of the register the arm 27 is horizontally extended, being thus 100 disposed in convenient position so that if the register herein described be located at the top of a room, manipulating devices of similar construction may be used to engage the handle 28. If the louvers be closed when 105 the arm 27 is in the horizontal position, by drawing downward the handle 28, the shaft 26 and segment 25 thereon are rotated to lift the bar 19 and the links 16 connected therewith. Lifting the links 16 results in 110 swinging the louvers 9 on the hinges 12, permitting the passage of air through the box.

10 and openings of the grill 11. Reversing the movement of the arm 27 results in reversing the operation of the louvers to close the openings at the back of the said box. In 5 any position to which the arm 27 and parts connected therewith is moved, the same is held constant by the drag of the washer 22 and bar 19 on the rib 20, being thereto actuated by the spring 23.

10 The shaft 26 is partly supported by the cross brace 31 extended between the vertical sides of the box 10. At the outer end of the said shaft and at the outer side of the grill 11 is provided a plate 32. The plate 32, 15 as shown best in Fig. 2 of the drawings, is provided with a projecting pin 33 extended into the path or, to be impinged upon by, the arm 27. This pin 33 limits the movement of the arm 27 when shifted to open the 20 louvers 9. The plate 32 is also adjustable, being rotatively mounted on the shaft 26. The edge of the said plate extends the head of the screw 34 which is employed in the 25 structure of the grill 11 to clamp the said plate 32 when set up against the same. By this it will be seen that by releasing the screw 34 the plate 32 may be rotated on the shaft 26 and be fixed in adjusted position to limit the movement of the arm 27, and 30 parts connected therewith, to any extent, thereby limiting the possible opening of the louvers 9.

While I have herein shown and described the register constructed and arranged in 35 accordance with the present invention as operated by the arm 27 and handle 28, it will be understood that without varying the scope of the invention the said handle and arm may be substituted by a key of any de- 40 sired and approved shape. The substitution thus indicated is particularly desirable for registers situated in the side wall of the room adjacent the floor, or in the floor of the said room. When the substitution indicated

is made the operation of the parts is in all 45 respects the same as above set forth.

Having thus described my invention, what I claim as new and desire to secure by Letters Patent is:—

1. In a ventilating register such as de- 50 scribed, the combination of a plurality of louvers adapted to close the opening of said register; a structural rib vertically disposed in said register; a slide bar mounted on said rib and having at suitable intervals perforations formed therein; a plurality of links connecting said bar and said louvers to rotate said louvers as said bar is reciprocated; a rotary shaft; a toothed segment having teeth to engage the said perforations in said 55 slide bar to move the same; manually manipulative means mounted on said shaft at the exposed side of said register; and a spring actuated clamp mounted on said slide bar to engage said rib to hold said slide bar 60 in adjusted position.

2. In a ventilating register such as de- 65 scribed, a box having a back opening; a louver pendants hinged on said box to cover said back opening; a manually reciprocated 70 member mounted within said box; and a link pivotally connecting said member and said louver, the connection of said louver and said link being projected to the outer side of said louver.

3. A ventilating register such as described; having a louver provided with hinge wings projected beyond the back of said louver; and rotating means for said louver embodying a link pivotally mounted between said 80 hinge wings.

In testimony whereof I have signed my name to this specification in the presence of two subscribing witnesses.

FREDERICK AUGUSTUS WILSON.
